A. R. RIDDERSTROM

FOLDING MACHINE

Filed Sept. 12, 1924

UNITED STATES PATENT OFFICE.

ANDREW R. RIDDERSTROM, OF NAHANT, MASSACHUSETTS, ASSIGNOR TO BEACON FOLDING MACHINE COMPANY, OF LYNN, MASSACHUSETTS, A CORPORATION OF MASSACHUSETTS.

FOLDING MACHINE.

Application filed September 12, 1924. Serial No. 737,310.

The present invention relates to folding machines.

The invention will be more fully explained in connection with the accompanying drawings, in which Fig. 1 is a perspective view, with parts broken away, of the forward portion of a machine embodying the present invention; Fig. 2 is a view of a detail; Fig. 3 is a similar view, showing the parts in relatively different positions; Fig. 4 is an elevation of a portion of the machine shown in Fig. 1; Fig. 5 is a detail plan, partly in section upon the line 5—5 of Fig. 4, looking in the direction of the arrows, parts being omitted for clearness; Fig. 6 is a section taken upon the line 6—6 of Fig. 8; Fig. 7 is a plan corresponding to the elevation of Fig. 4; and Fig. 8 is a fragmentary elevation corresponding to Fig. 4, the scale being somewhat larger than in the other figures and parts being broken away for clearness.

The invention is illustrated in its preferred form as applied to a folding machine for folding the margins of shoe uppers, such as vamps, quarters and the like. The machine is provided with a lower feed block 41 and an upper feed point 30 between which a sheet of flexible material like a shoe upper 2, is adapted to be intermittently gripped, and by which it is adapted to be fed or advanced, step by step, over a platform or support 24. During this feed movement, the edge of the shoe upper first engages a gage 436, that is secured at 438 to the upper end of a bracket 61, after which it is advanced to and past two cooperating knives 352 and 353. The knife 353 is stationary, but the knife 352 may be thrown into operation, at the will of the operator, so as to snip or slit the margin of the upper, at will, and to this end, it is pivoted at 356 on the upper end of the same bracket 61, and is connected by a link 354 to mechanism (not shown) under the control of the operator, as is more fully explained in a co-pending application, Serial No. 652,169, filed July 17, 1923. Whether the margin is snipped or not, as may be desired, it is then advanced beyond a retainer 153 that acts to hold the stock against the support during pauses in the feed, but that is raised during the feeding movement. The other functions performed by the retainer and the retainer-operating mechanism will not be described

herein, because fully described in copending applications, Serial Nos. 352,987, filed January 21, 1920, which matured on February 24, 1925, into Patent No. 1,527,395, and 407-336, filed September 1, 1920, and because other retainers and other retainer-operating mechanisms may be employed without departing from the present invention. A plow 32, the folding nose 134 of which is preferably situated immediately to the rear of the retainer, as described in the aforementioned application, Serial No. 652,169, then acts to initiate a fold in the margin of the material, and a fold presser 42 subsequently presses the fold flat against the body of the material. The parts are compactly positioned, to enable operation upon stock having very sharp corners. The feed mechanism remains idle while the fold presser is pressing the fold, and the fold presser is ineffective during the feeding of the work.

The fold presser 42 is floatingly pivoted at 146 to a link 148 the other end of which is operated from a driving shaft 66, as is more fully described in the above-mentioned Patent No. 1,527,395. The exterior surface of the fold presser is cylindrical, as shown at 156 so as to rock within a cylindrical bearing 158 provided at the free end of an arm 160 the other end of which is pivoted at 162. The fold presser is spring-pressed towards the support 24 by a compression spring 166 mounted upon a rod 168 extending through an opening 144 in the arm 160 and screw-threaded into the frame, as shown at 145. By means of the screw threads, the pressure of the spring upon the arm 160 may be adjusted, the ends of the spring being confined between the arm and a kerfed head 170 upon the rod 168. By means of this construction, the fold presser is pivotally actuated in a plane at right angles to the plane of feed, with a yielding action of the fold presser upon the fold, relieving the strain thereon, while permitting a positive separation of the fold presser from the upper by the link 148.

The feeding mechanism, comprising the feed block 41 and the feed point 30, is also driven from the driving shaft 66 by mechanism more fully described in the above-named Patent No. 1,527,397. The feed block 41 is shown more particularly in Fig. 4 as rigidly secured to, or integral with, a holder 93 that

is secured, as by a set screw (not shown), to a rocking or oscillating support 94. The rocking support is pivotally mounted about a rod 96 that is secured to the frame of the machine by a screw 98. The feed point 30 is pivotally mounted at 110 upon the rocking support 94, so as to be rocked therewith and with the lower feed block 41.

An arm member 36 is also pivotally mounted to rock or oscillate about the rod 96. The member 36 is provided with a diagonally disposed cylindrical opening 100 within which is slidably mounted a diagonally cylindrical block 102 the upper flat face of which is substantially horizontal, as shown at 104. The angle of inclination of the opening 100 is preferably in the neighborhood of thirty degrees. The cylindrical block 102 is adapted to be actuated by an eccentric or crank pin 106 of the driving shaft 66. The eccentric or crank pin is rotatably mounted in the block 102 and extends through an opening 108 of the rocking member 36. Rotative movement of the shaft 66 will be converted by the eccentric into combined sliding and oscillating or rotative movement of the block 102 and this, in turn, will effect a rocking movement of the rocking member 36 about the rod 96. A compression coiled spring 38, interposed between the rocking support 94 and the rocking member 36, yieldingly connects the rocking support 94 to the rocking member 36 to cause them to rock or oscillate together, as a unit. The coiled spring 38 yieldingly maintains an arm 39 of the rocking support 94 in engagement with an adjustable portion 40 of the rocking member 36. The adjustable portion 40 of the rocking member 36 is shown as a set screw. The feed point 30 is normally yieldingly maintained in contact with the feed block 41 by a compression coil spring 112 coiled about a threaded rod 114 extending through an opening 116 in the feed-point arm 118 and secured at 43 to the rocking support 94. By means of the threads upon the rod 114, the pressure of the spring 112 upon the feed point may be adjusted, the ends of the spring being confined between the feed-point arm 118 and a knurled nut 124 that is threaded upon the rod 114. The feed-point arm 118 is provided with an adjustable screw 120. The upper face 104 of the block 102 is adapted to engage the screw 120, thereby to raise the feed point, in opposition to the pressure of the spring 112. An additional adjustable member 123 is provided to prevent the feed point becoming lowered into contact with the feed block when the machine is running idly, thereby preventing the feed point pounding uselessly against the feed block when no stock is interposed.

As the driving shaft 66 is rotated, the rocking support 94 is rocked from right to left and from left to right, as viewed in Fig. 6, imparting an oscillating movement to the

lower feed block 41 and the upper feed point 30 which are carried thereby. During the left-to-right movement, the feed point 30 will be separated from the feed block 41 by the action of the cylindrical block 102, which then occupies its upper positions. During the right-to-left movement, the block 102 will lie in the lower portions of the cylindrical opening 100, and the feed point will be spring-pressed into engagement with the feed block, which will thus advance to the fold presser the upper clamped therebetween.

Curved portions of the work should not be fed so rapidly as straight portions. To vary the lengths of the feed steps, so as to feed the work by greater or by shorter feed strokes, at will, the rocking support 94 may be adjusted angularly closer to, or farther from, the rocking member 36. This is accomplished, as is more fully illustrated and explained in the application Serial No. 652,169 aforesaid, by pressing upward upon an arm 45 that projects out from the arm 39 of the rocking support 94, as shown clearly in Fig. 1. The free end of the arm 45 is adapted to be engaged by the free end of an arm 122 that is pivoted to the frame of the machine at 143. Pivotal movement of the arm 122 may be effected by a vertically disposed arm 145 the upper end of which is pivoted to the arm 122 at 147. The lower portion of the arm 145 is adapted to be engaged by actuating a cam member 46 that is secured to one end of a rock shaft 170 that extends transversely across the machine, as indicated more particularly in Fig. 1.

The plow 32 is intermediately carried upon a lever 34 one end of which is pivoted at 130 to the frame of the machine in such fashion as to permit the lever to pivot in a horizontal plane, as is more fully described in a co-pending application, Serial No. 668,345, filed October 13, 1923. The plow therefore moves in substantially the plane of the upper, but at an angle to the direction of feed. The other end of the lever 34 is yieldingly maintained in engagement with a projection 37 of the arm 36 by a leaf spring 132 that is fixed to the arm 36 in any desired manner, as illustrated at 140. When the arm 36 is rocked downward, as viewed in Figs. 5 and 7, the projection 37 will engage the lever 34 and cause the plow 32 to swing open about its pivotal point 130, in the direction of the curved arrow, Fig. 5. When the arm 36 is rocked in the opposite direction, the spring 132 will cause the plow to pivot in the opposite direction. The plow is thus oscillated once corresponding to each rocking movement of the rocking arm 36.

Before the machine is started, it is desirable to raise the feed point from the feed block to permit the insertion of the upper therebetween. The screw 123 of the feed point is adapted to rest upon the rocking support 94, as before described, but the feed point is

adapted to be raised, in opposition to the force of the spring 112, by a rod 300 that is vertically disposed in an opening 302 of the rocking support 94. The rod 300 rests upon the head of a rod 304 that is slidably mounted in a vertical opening 306 provided transversely through the rod 96. The rod 304 is adapted to be raised by mechanism under the control of the operator, as is more fully described in the above-named applications, Serial Nos. 652,169 and 668,345.

Summarizing the operation of the preferred machine, as thus far described, the shoe upper is advanced over the support 24, step by step, by the feed point 30 and the feed block 41; the plow 32 is actuated during pauses in the feed to initiate a fold in successive portions of the margin, step by step; and the fold presser 42, preferably situated immediately before the plow in the line of feed, is actuated step by step, during pauses in the feed, to press flat the folds successively initiated by the fold presser during immediately prior pauses in the feed. Each folded portion is pressed while the next succeeding portion is being folded. The feed elements may feed by shorter or longer feed steps, as desired.

If the work is sharply convex, as illustrated in dotted lines in Fig. 5, it has a tendency to be fed out of range of operation of the fold presser. Provision is therefore made, according to the present invention, for moving the fold presser at right angles to the line of feed, during the operation of the machine, so as to maintain an active cooperative relation between the fold presser and the work. According to the specific embodiment of the invention that is herein illustrated and described, this result is effected by moving the arm 160 bodily at right angles to the line of feed. The pivot 162 is therefore mounted upon an arm 177. The arm 177 is pivotally mounted to the frame of the machine at 179, so as to pivot in a plane at right angles to the line of feed. A pivotal movement of the arm 177 in one direction will effect a corresponding movement of the arm 160; and a reverse movement of the arm 177 will result in a corresponding reverse movement of the arm 160. The first-named movement of the arm 177 may be effected by a screw 181 that is adjustably threaded in a projecting portion 183 of the arm 177 and that engages a portion 185 of the machine frame. The reverse movement may be effected by a spring 187 one end of which is secured to the projecting portion 183 at 189 and the other to a stationary part of the frame of the machine at 191. The movement of the arm 160 will, of course, have some result upon the operating effect of the link 148 upon the fold presser 42. This result will be negligible, however, for two reasons: first, the amount of movement of the arm 160 is relatively small; and secondly, be-

cause the fold presser descends with a rolling action.

Many details of the illustrative machine have not been illustrated herein, and many illustrated parts have not been described, because unnecessary to an understanding of the present invention, and because full particulars may be obtained in the aforesaid applications. The elements of novelty, furthermore, though fully explained, are by no means restricted to the exact embodiments thereof that are illustrated and described herein. Modifications and changes will readily occur to persons skilled in the art, and all such are considered to fall within the scope of the invention, as defined in the appended claims.

What is claimed is:

1. A folding machine having, in combination, means for feeding material, means for folding the material, a fold presser for pressing the fold, a member pivoted to the fold presser about a pivotal point, means for actuating the member to actuate the fold presser into and out of contact with the fold, and means for adjusting the fold presser about the pivotal point in a direction at an angle to the line of feed.

2. A folding machine having, in combination, means for feeding material step by step, a plow for initiating a fold in the margin of the material, means for actuating the plow to initiate the fold in successive portions of the margin step by step, a fold presser, a member pivoted to the fold presser about a pivotal point, means for actuating the member to actuate the fold presser into and out of contact with the fold to press the fold step by step, and means for adjusting the fold presser about the pivotal point in a direction at right angles to the line of feed.

3. A folding machine having, in combination, means for feeding material, means for folding the material, a rolling fold presser for pressing the fold, means for rolling the fold presser, and means for pivotally adjusting the fold presser in a direction at right angles to the line of feed.

4. A folding machine having, in combination, means for feeding material, a plow for initiating a fold in the margin of the material, a fold presser for pressing the fold initiated by the plow, a link connected with the fold presser for actuating the fold presser, and means for adjusting the fold presser about its point of connection with the link in a direction at right angles to the line of feed.

5. A folding machine having, in combination, a support, means for feeding material over the support, a retainer for holding the material against the support, means for folding the material, a fold presser for pressing the fold, means for actuating the fold presser into and out of contact with the fold, and means for pivotally adjusting the fold presser

in a direction at right angles to the line of feed.

6. A folding machine having, in combination, means for feeding material, means for folding the material, a fold presser for pressing the fold, an arm upon which the fold presser is mounted so as to move with respect to the arm, means connected with the fold presser for actuating the fold presser with respect to the arm into and out of contact with the fold, and means for adjusting the arm in a direction at an angle to the line of feed.

7. A folding machine having, in combination, means for feeding material, means for folding the material, a fold presser for pressing the fold, an arm to which the fold presser is pivoted about a pivotal point, means for pivotally actuating the fold presser upon the arm about the pivotal point into and out of contact with the fold, and means for adjusting the arm in a direction at an angle to the line of feed.

8. A folding machine having, in combination, means for feeding material, a plow for initiating a fold in the margin of the material, a fold presser for pressing the fold initiated by the plow, means for pivotally actuating the fold presser in a plane at right angles to the line of feed into and out of contact with the fold, and means for pivotally adjusting the fold presser about its point of pivotal actuation in the said plane in a direction at right angles to the line of feed.

9. A folding machine having, in combination, a support, means for feeding material over the support, a retainer for holding the material against the support, a plow for initi-

ating a fold in the margin of the material, a fold presser for pressing the fold initiated by the plow, an arm upon which the fold presser is mounted, means for pivotally actuating the fold presser upon the arm in a plane at right angles to the line of feed, and means for adjusting the arm at right angles to the line of feed to adjust the fold presser in a direction at right angles to the line of feed.

10. A folding machine having, in combination, a movable plow for folding the margin of material, a pivotally mounted support, a feed block rigidly secured to the support, a feed point pivoted to the support, an arm pivotally mounted about the pivotal axis of the support having a diagonally disposed cylindrical opening, a diagonally cylindrical block slidingly mounted in the opening, an eccentric for actuating the block to cause the oscillation of the arm, means yieldingly connecting the arm and the support, the feed block and the feed point being adapted to feed the material step by step to the plow during the forward oscillation of the arm and the support, the block being adapted to separate the feed point from the feed block during the return oscillations of the arm and the support, means for adjustably limiting the degree of oscillation of the support to adjustably limit the extent of feeding action of the feeding means, a fold presser, and means for adjusting the fold presser in a direction at an angle to the line of feed.

In testimony whereof, I have hereunto subscribed my name this 6th day of August, 1924.

ANDREW R. RIDDERSTROM.
